Primary Examiner — Paula Greene(74) *Attorney, Agent, or Firm* — McAndrews Held & Malloy, Ltd.**CLAIM**

The ornamental design for a portable electronic device, as shown and described.

DESCRIPTION

FIG. 1 is a bottom right front perspective view of a portable electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of the portion encircled in FIG. 6.

The even length dashed broken lines represent unclaimed portions of the portable electronic device and form no part of the claimed design.

In FIGS. 6 and 8, the uneven length dot-dash broken lines encircling a portion of the claimed design for illustrating an enlargement form no part of the claimed design.
